UNITED STATES PATENT OFFICE.

JOSEPH LUCE, OF SALT LAKE CITY, UTAH.

APPARATUS FOR TREATING ORES BY LIXIVIATION.

SPECIFICATION forming part of Letters Patent No. 620,660, dated March 7, 1899.

Application filed April 27, 1898. Serial No. 679,046. (No model.)

To all whom it may concern:

Be it known that I, JOSEPH LUCE, a citizen of the United States, residing at Salt Lake City, in the county of Salt Lake and State of Utah, have invented certain new and useful Improvements in Apparatus for the Treatment of Ores by Lixiviation; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to an apparatus for the treatment of ores by lixiviation; and it consists, first, in a tank for the treatment of ores, provided with a filtering-lining which is applied to its inner side, combined with suitable supports placed inside of the lining, steam-pipes which extend back and forth in the tank, and vertical layers of cloth arranged inside of the pipes, an agitator-tank, a second tank placed below the agitator-tank, and a suitable supply-pipe which connects the two, suitable filtering-linings applied to the inner sides of the tanks, and an agitator placed in the upper tank, and, second, in the construction and arrangement of parts, which will be more fully described hereinafter, whereby ores of all metallic minerals—crude, concentrated by mechanical manipulation or smelting, &c., and containing copper, gold, silver, or other metals—are treated by lixiviation, so as to extract the metal rapidly and economically.

In the accompanying drawings, Figure 1 is vertical sectional view of an apparatus which embodies my invention complete. Figs. 2 and 3 are enlarged sectional views of the lining applied to both the agitator and the tank. Fig. 4 is a vertical section of the tank A on an enlarged scale. Fig. 5 is a vertical section of the tank P, also on an enlarged scale.

A represents a sheet-iron conical tank of suitable size which is provided at its upper and larger end with a convex cover B, upon which is mounted suitable supports C, in which is journaled the shaft D, provided with beveled gears E, placed in reverse positions toward each other. The shaft D is driven by means of the pulley F continuously in the same direction, while the two gears E are al-

ternately brought into contact with the beveled gear G, secured to the upper end of the shaft H, according to the direction in which the shaft is to be driven. Secured to the shaft is a series of blades I, and to the lower end of the shaft is secured a screw conveyer J. Upon the lower end of this tank is secured the reservoir K, into one side of which the pipe L extends for the purpose of feeding in the solution which is to be used in connection with the reduced ore, which is fed into the tank through the two manholes or openings M of any convenient shape. The lower portion of the screw conveyer is inclosed within a suitable tube N, which is closed in any suitable manner until the contents of the tank are to be discharged, and then the lower end of the tube is opened and the screw made to revolve in the proper direction, when the whole contents of the tank are discharged through a suitable connection O, or the agitator may be placed so closely above the larger tank P that it can discharge directly into it.

The tank P, which is much larger than the one A, is also made of riveted sheet-iron and sufficiently strong to stand a pressure of sixty pounds and which is supported at its smaller lower end by the iron ring Q and the standards R. This tank is also provided with a conical air-tight cover B', through which is made a suitable manhole S, through which the mixture from the tank A is admitted. Also through this cover B' is passed the pipe T, through which the air-pressure is admitted.

At the lower end of the tank P is formed the cylindrical sheet-iron reservoir U, and leading into the bottom of this reservoir on one side is the pipe V, through which the solution is fed, and extending from the opposite side is the pipe W, through which the solution is removed. The bottom X of this reservoir is made removable, so as to form a manhole to enable the tank and reservoir to be cleaned when necessary. Inside of this reservoir C is placed a smaller perforated wall, as shown. The bottom Y of the tank A is made inclined, as shown, toward the screw conveyer Z, which extends horizontally through the tank and is driven by the pulley A' upon one end of its shaft. The outer end of the tube in which the conveyer is placed is made removable, so that the tailings can be

readily removed when the leaching is completed.

Inside of both the agitator-tank and the large tank P is placed a drainage-lining, as shown more fully in Figs. 2 and 3 and through which the solution is made to pass in being forced into both of the tanks from the supply-pipes. This lining consists of a suitable thickness of asbestos C', which is applied 10 against the wall of the tank with asphaltum-varnish. Against the outer side of this asbestos lining is placed a thick coating D' of asphaltum-varnish. Placed inside of the asbestos lining are the drainage-boards E', which are made in short sections and provided with saw-teeth-shaped grooves, as shown in Fig. 3, so as to accommodate not only the pipes G', but to allow the drainage and the flow of the solution to take place freely. In 15 these grooves are placed the steam-pipes G', which are heated by exhaust-steam and which excite the solution of the metallic salts and allow a more perfect percolation and drainage of the pulp. Against the inner edges of the 20 boards E' are placed the boards F', which are provided with longitudinal grooves H' and perforations I' to allow the solution to pass from the tank into the drainage-lining. Against the inner faces of the boards F' are 25 stretched sheets of cloth J' over the grooves in the boards F', so as to assist in the straining of the solution. Against the inner sides of the layers of cloth J' are placed the boards K', similar to those F' and which are also provided with longitudinal grooves L' and perforations O', but which perforations slant 30 downward to avoid the accumulation of slimes in the holes. The perforations I' in the boards F' extend about horizontally, as they are protected from the accumulation of slimes therein by the layers of cloth. 35

Above the lining just described is placed the lining P', made of solid wood and which closes the upper part of the drainage-lining 40 to prevent the direct action of the compressed air upon the solution contained in the drainage-lining during the drawing off of the solution from the tank.

The operation of my machine is as follows: 45 The bottom of the tube N in the agitator-tank A being closed, proper solution is introduced through the pipe L into the reservoir K and from which it rises and passes through the lining into the center of the tank A until the 50 tank is two-thirds full, when the shaft H, provided with the blades I and the screw conveyer J, is set into operation by means of the pulley F. The conveyer being a right-hand screw, the first motion given will be a 55 left-hand circular motion, the purpose of which is to keep the conveyer free from pulp and give to the solution and pulp an ascending motion, thus producing a greater and more thorough stirring of the mass. The reduced ore is then introduced into the tank A 60 through the openings M in the top of the

cover B, and this ore is brought into direct contact with the solution and triturated into a pulp of a medium consistency. The blades I also serve to agitate and more thoroughly mix the ore with the solution. The agitator being filled with pulp of the proper thickness, the cover or other device used for closing the other end of the pipe N is removed, and the motion of the shaft H is reversed by 70 the shifting of the shaft D or the gears secured thereto. The solution is allowed to flow into the agitator by the pipe L, as is also the ore from the storage-bins. The pulp is then conveyed and discharged by the screw 75 conveyer J and fed to the leaching-tank P through the manhole S. This leaching-tank has previously been filled with proper solution through the inlet-pipe V, the outlet-pipe W being closed. After the pulp from the 80 agitator-tank has been discharged into the leaching-tank P the manhole S is closed airtight. The pulp in reaching the solution in the tank P diffuses readily and settles down in the tank by its own gravity. After the 85 tank has been filled the inlet-pipe V is closed. Compressed air is then introduced through the pipe T at a pressure of from eight to ten pounds, and the contents of the tank are allowed to remain under pressure for about two 90 hours, when the pressure is increased to fifteen or twenty pounds. The outlet-pipe W is then opened, and the solution now loaded with the metals under treatment is allowed to run out and stored ready to be submitted 95 to further metallurgical treatment. The leaching-tank is emptied through the horizontal screw conveyer Z, placed at the bottom of the tank, and this operation takes place as soon as the solution has been drained 100 off. The pressure in the tank assists in the removal of the pulp. The amount of pulp removed by this operation is equal to one-eighth of the capacity of the tank. The cap of the screw conveyer Q is then opened and 105 the screw conveyer set in motion by the pulley A'. The pulp is discharged either in wheelbarrows, carts, belt conveyers, or any other devices. The solution having been drained off and one-eighth part of the pulp being removed, the outlet-pipe W is closed, as is also the pipe T for the admission of compressed air. Fresh solution is forced into the tank 110 through the inlet-pipe V, and this penetrates into the tank through the strainer applied to 115 the inner side of the tank. When the tank is filled, the inflow of the solution is stopped. A new batch of pulp is also fed into the tank 120 from the agitator A, the manhole is closed, compressed air is again introduced, and another leaching operation takes place. 125

Two hours has been found most favorable for the leaching under pressure and one hour for the different manipulations of emptying and refilling the one-eighth capacity of the 130 tank, making a total of three hours for each separate leaching. These successive leach-

ings of regular length tend to give an average solution uniform to the metals contained in it.

The systematic succession of the different operations makes my apparatus thorough and economical in the results obtained.

By means of the agitator I bring the molecules of the fine ore into closer contact with the molecules of the solution before the leaching process begins, and by feeding the pulp into the hot solution in the leaching-tank the ore diffuses more readily through the liquid and is more thoroughly impregnated by it. By the application of heat and pressure through the introduction of steam and compressed air into the leaching-tank a complete and prompt solution of the metallic salts contained in the ore is obtained. By the application of compressed air during the drainage I excite and render more thorough the percolation of the liquid through the ore, and it shortens considerably the length of duration of the leaching process. Also by the use of compressed air during the discharge of the tailings the time for this operation is shortened very materially. By unloading the leaching-tank between each leaching brings a series of modifications in the relative position of the molecules of the pulp in the tank, and this produces a more intimate contact between them and the solution, the result being a thorough leaching. Also by the partial unloading of the tailings of the tank and the partial loading of the fresh pulp I obtain an average mixture whose leaching by a standard solution cannot fail to give a standard electrolyte, so advantageous to the success of subsequent treatments, either chemically or by electrolysis.

The drainage-lining applied to both the agitator and the leaching-tank is compact in its construction and of great efficiency. It presents a large capacity for filtration and is not liable to clog, as it cleans itself by the alternate passage of the solution in opposite directions during the operations, first, in filling the tank with the solution, and next during the drainage process, when the flow is reversed. By removing the solution from the tank with the help of compressed air I avoid the stirring of the mass of the pulp and of the

solution. By doing so I prevent the molecules from coming unnecessarily in contact with the outside fresh air and being acted upon by it.

55

The conical shape of the tanks allows the wet pulp to slide down the walls of the leaching-tanks without any mechanical help, and such sliding motion takes place by the simple action of gravitation. This construction is especially fitted to treat large quantities of ore most economically. The combination of heat and pressure in connection with the apparatus here shown and described is specially advantageous.

65

In Fig. 1 of the drawings the screw is shown as being placed in a line with the pipes V W; but in actual practice they will preferably be placed at right angles to each other.

Having thus described my invention, I claim—

1. In a tank for the treatment of ores, a lining of asbestos which is applied directly to and covers the walls of the tank, combined with suitable supports placed inside of the asbestos, steam-pipes supported in the tank, and vertical layers of cloth arranged inside of the pipes, substantially as described.

75

2. In a tank for the treatment of metals, a lining composed of a thickness of asbestos applied to the inner side of the tank, boards E' extending vertically in the tank inside of the asbestos, and provided with suitable recesses, and steam-pipes placed in the tank, and supported in the recesses formed in the edges of the boards, substantially as set forth.

80

3. In a tank for the treatment of ores, a lining composed of asbestos applied to the inner side of the tank, the notched or recessed boards applied inside of the asbestos, and the steam-pipes placed in the notches in the boards, combined with two thicknesses of grooved perforated boards, and the layers of cloth between the boards, substantially as specified.

85

In testimony whereof I affix my signature in presence of two witnesses.

95
